CLAIM

The ornamental design for a paper feeder for printer, as shown and described.

DESCRIPTION

FIG. 1 is a top, front and right side perspective view of a paper feeder for printer showing my new design, the broken lines are for purposes of illustration only and form no part of the claimed design;

FIG. 2 is a top plan view thereof;

FIG. 3 is a front elevational view thereof;

FIG. 4 is a right side elevational view thereof with the left side being the mirror image of the right side shown;

FIG. 5 is a rear elevational view thereof; and,

FIG. 6 is a bottom plan view thereof.

FIG. 1

FIG. 2***FIG. 3******FIG. 4******FIG. 5******FIG. 6***
